Primary Examiner — Brett Miller*Assistant Examiner* — Mary Anne Arntzen(74) *Attorney, Agent, or Firm* — Goldstein Law Offices, P.C.(57) **CLAIM**

The ornamental design for a wooden scorekeeper, as shown and described.

DESCRIPTION

FIG. 1 is a perspective view of a wooden scorekeeper in accordance with the present invention; FIG. 2 is a top plan view thereof; FIG. 3 is a bottom plan view thereof; FIG. 4 is a front elevation view thereof; FIG. 5 is a rear elevation view thereof; FIG. 6 is a left side elevation view thereof; and, FIG. 7 is a right side elevation view thereof. The broken lines in the drawings depict portions of the wooden scorekeeper that form no part of the claimed design.
